UNITED STATES PATENT OFFICE.

GEORGE WASHINGTON, OF TOMPKINSVILLE, NEW YORK.

HYDROCARBON INCANDESCENT LAMP.

SPECIFICATION forming part of Letters Patent No. 760,672, dated May 24, 1904.

Original application filed November 8, 1898. Renewed January 22, 1901, Serial No. 44,301. Divided and this application filed March 20, 1902, Serial No. 99,094. (No model.)

To all whom it may concern:

Be it known that I, GEORGE WASHINGTON, of Tompkinsville, in the county of Richmond and State of New York, have invented certain new and useful Improvements in Hydrocarbon Incandescent Lamps; and I do hereby declare the following to be a full, clear, and exact description of the invention, such as will enable others skilled in the art to which it appertains to make and use the same.

My invention relates to an improvement in hydrocarbon incandescent lamps, and is a division of application Serial No. 44,301, renewed January 22, 1901.

My invention consists in the parts and combination of parts, as will be more fully explained, and pointed out in the claims.

In the accompanying drawings, Figure 1 is a view in section of a lamp embodying my invention; and Fig. 2 is a view, partly in section and partly in elevation, of a modification thereof.

1 represents a vaporizing-tube provided at its lower end with a removable plug 2, having a central longitudinal opening for the passage of a needle - valve, which latter is suitably packed to prevent the escape of any oil. This vaporizing-tube is supplied with oil by any suitable means—as, for instance, by oil-pipe 3—and is provided at its discharge end with nozzle 4, which latter has a tapering bore through which the needle 5 passes.

The upper end of the vaporizing-tube 1 is secured to or made integral with the base 11, which latter acts as a heat-accumulating body for heating the vaporizing-tube. Secured to the base 11 is the upwardly-projecting commingling-tube 12, into which the vapor is discharged, and surrounding the commingling or inner tube 12 is an outer longer burner-tube 13. In the construction shown in Fig. 1 the upper end of the commingling - tube 12 is open and the top of the burner-tube closed, and the latter is provided at a point between its ends with a plurality of burner-tubes 44, each of which is provided with a mantle. Instead, however, of attaching a plurality of burners to the tube 13 at a point between its

ends it is evident that a plurality of burners can be connected near the top of burner-tube 50 and above the commingling-tube 12, as shown in Fig. 2. In this construction of lamp air-inlets 45 pass into the commingling-chamber through the base 11 at a point below the auxiliary heater and discharge the air adjacent 55 to the discharge end of the vapor-nozzle, so that the air and vapor will be thoroughly intermixed in their passage through the commingling-tube. The vapor as it issues from the vapor-escape nozzle draws in air through 60 the openings 45, and the air and vapor thus brought together are commingled and pass upwardly. In the construction shown in Fig. 1 all of the mixed air and vapor is deflected by the closed top of the burner-tube and passes 65 downwardly, while in Fig. 2 a part passes upwardly to the burners 14 and a part down around the commingling-tube 12. In both instances, however, a part of the mixed air and vapor passes down to the base 11, which 70 is provided with a series of jet-orifices 22, and the mixed air and vapor escaping through these orifices is burned in direct contact with the base, the flames from the several jets impinging against the flanges 24, thus quickly 75 heating the base and maintaining it at such a temperature as to quickly vaporize the oil within the upper portion of the vaporizing-tube. The vaporization of the oil may be started by heating the generating-tube 1 in any 80 manner; but I prefer to provide it with a starting-cup designed to contain sufficient alcohol or oil for the initial heating of the generating or vaporizing tube. After the vapor begins to form it enters the burner-tube and filling same 85 a part of it escapes through the vapor-escape orifices or auxiliary heater 22 and will be ignited by the flame from the starting-cup, and as these jets impinge directly on the flange 24 of the base the latter will quickly be heated to a 90 temperature sufficient to continue the vaporization of the oil.

It is evident that many slight changes might be resorted to in the relative arrangement of parts shown and described without departing 95 from the spirit and scope of my invention.

Hence I would have it understood that I do not wish to limit myself to the exact construction of parts shown and described; but,

Having fully described my invention, what 5 I claim as new, and desire to secure by Letters Patent, is—

1. The combination with a main burner-tube, and a mixing or commingling chamber within the same, of a jet-nozzle extending into 10 the commingling-chamber, means for discharging air into the commingling-chamber, an auxiliary burner adjacent to the discharge-nozzle and receiving its vapor from the main burner-tube, and a plurality of burner-tubes 15 extending from said main burner-tube, substantially as described.
2. The combination with a commingling-chamber, means for discharging air into said chamber, a casing surrounding and inclosing 20 the commingling-chamber, and a plurality of burners each directly connected with this casing, of a vaporizing-tube having its discharge end terminating within the commingling-chamber, and an auxiliary burner at the base 25 of the casing and adjacent to the base of the commingling-chamber, for heating the discharge end of the vaporizing-tube, substantially as set forth.
3. The combination with a commingling-

chamber, means for discharging air into said 30 chamber, a casing surrounding the chamber, and a plurality of burners each connected directly with the casing at points above the air-inlet, of a vaporizing-tube discharging into the commingling-chamber adjacent to the air-inlet, and an auxiliary burner at the base of the casing for heating the discharge end of the vaporizing-tube, substantially as set forth. 35

4. The combination with a commingling-chamber, a casing surrounding same, means 40 for discharging air into said commingling-chamber, and a plurality of main burners each connected directly to said casing, of a vaporizing-tube discharging into the commingling-chamber adjacent to the egress ends of the 45 air-inlets, and an auxiliary burner at the base of the casing and above the ingress ends of the air-inlets, the said auxiliary burner adapted to heat the discharge end of the vaporizing-tube, substantially as set forth. 50

In testimony whereof I have signed this specification in the presence of two subscribing witnesses.

GEORGE WASHINGTON.
